American Machine & Metals, Inc., East Moline,
Ill., a corporation of Delaware

Application December 11, 1943, Serial No. 513,915

4 Claims. (Cl. 68—12)

1

The present invention relates to improvements in Automatic Textile Washing Apparatus.

It is common practice in the commercial washing of textile pieces to place them in a heap in a rotatable container, usually mounted for rotation about a horizontal axis, the lower part of the container passing through a bath. This bath is usually made up of a detergent solution at some stages of the process and usually consists of plain water, or at least of a progressively diluted bath, at the rinsing stages in the process. At certain stages the bath may contain dilute solutions of bluing or other material. Commonly the cylinder is equipped with internal ribs or their equivalents, and as the cylinder is rotated about its horizontal axis the textile pieces are immersed in the bath at intervals, the ribs lifting the pieces from the bottom of the heap out of the bath and letting them slide off onto the top of the heap. While the invention will be described as applied to a washer having a perforate cylinder adapted to revolve in a stationary shell, it will be understood as the description proceeds that the invention is also applicable to the so-called shell-less washer in which a single revolving cylinder serves to enclose both the textile pieces to be cleaned and the detergent or rinsing solution. The type of washer as commonly used in commercial laundries employs a perforate rotatable cylinder mounted within a shell, the bath being contained within the shell and having a liquid level located below the axis of rotation of said cylinder. Said liquid level will be correlated to the size of the heap of textile pieces in the cylinder and ordinarily will be higher during the rinsing operations than during the sudsing operations. The rate of rotation of the cylinder is, according to common practice, sufficient to lift some of the textile pieces out of the bath, separating the pieces from the mass, the portion lifted out of the bath sliding off the rib that lifted it as the angle which the rib makes with the horizontal becomes steeper. The pieces slide off the rib and fall back on top of the mass of pieces in the bath.

The speed of rotation must, according to preferred practice, be held within rather close limits for efficient washing because upon the speed of rotation depend the degree of intermingling of the parts of the mass of textile pieces, the height to which the particular pieces are carried, the location where they will strike when the particular pieces fall back, and how hard said pieces will strike. Efficient washing requires that the parts of the mass of textile pieces be kept in constant

2

movement relative to each other so that each part is exposed to the bath. If it were otherwise, soil might be trapped in a tightly closed fold which might never be exposed to the fresh detergent of the bath.

The invention is particularly applicable to the washing of large loads of such objects as sheets, towels, shirts and the like. The tumbling action described is designed to break up the mass of 10 textile pieces by separating adjacent pieces and rearranging them. The tumbling action will separate small objects such as wash cloths or handkerchiefs, but the several parts of a large piece, such as the arms and tail of a shirt, may 15 be carried off in opposite directions within the mass, with the result that articles like shirts tend to become intertwined. Instead of separating the pieces of clothes, tumbling in some instances has the result of intertwining them.

20 The amount of tangling is related to the speed of rotation of the cylinder, and if the speed thereof is high enough the centrifugal force generated will cause the work to "ride around" and not tumble at all. In small machines such as 25 household machines this problem is minimized because the small capacity limits the load to only a few pieces and the speed can be held closer to that speed at which the clothes do not tend to tangle.

30 In commercial operation, however, efficiency of operation and the necessity for exposing all parts of the mass to the washing action call for operating speeds at which tangling is a serious problem. Where the washing cylinder is loaded with 35 a relatively large mass, which may weigh as much as 700 pounds when wet, the grasping of a shirt entangled with other garments and pulling it loose in unloading the washer can readily tear the shirt. Much time is lost in picking up several pieces to see which can be pulled free most easily.

40 It has been common practice to operate commercial washers according to a program which calls for reversing of the direction of rotation of the washer cylinder after every three or four 45 revolutions on the theory that pieces dragged into a half-tied knot running in one direction tend on reversal to be dragged apart again.

50 Reversing the direction of rotation of the washer cylinder requires the cutting off of the driving force, applying the brake, or allowing the washer to slow down, re-engaging the driving force in the opposite direction, supplying the energy drive necessary to start the cylinder from rest against the resistance of the liquid bath;

counting the number of revolutions, and repeating the process. While the washer cylinder is slowing down, reversing and picking up speed in the opposite direction, very little washing action takes place. There is a substantial loss of time during the coasting to a stop, the actual stop, and the reverse acceleration.

Washer cylinders according to certain preferred practice are controlled automatically to carry out certain predetermined programs, which control involves the operation of instrumentalities responsive to the increase in volume of the contents of the washer while the washer cylinder is being rotated. In some instances the control is determined by the liquid level and/or the suds level of the bath, it being remembered that the level of liquid in the washer is influenced by the presence of suds therein. Reversal of rotation of the cylinder adds difficulties to such control of the washing operation for the reason that the revolving cylinder acts as a paddle wheel carrying the liquid up with it on one side, lowering the level at the other side. When the cylinder is rotating the liquid level in the washer is not a horizontal surface, but is an irregular surface. The effect of cylinder reversal is akin to a rising and falling tide level, and a device set to operate when a given level is reached will function differently if the level is reached while the washer cylinder is running in one direction than it will when the washer cylinder is running in the reverse direction. In short, there is a decided advantage in avoiding cylinder reversal during the washing period even though reversal is often required during the rinsing period.

It has been discovered that the textile pieces will not tangle and there is no need for reversal of cylinder rotation as long as detergents are present in the bath. It may be that the soap or other detergent in the bath acts as a lubricant, lowering the coefficient of friction of the fabrics as they slide over each other, so that, for example, if the sleeve of a shirt tends to tangle itself the body of the shirt can drag the sleeve with it without tangling.

The present invention contemplates, therefore, unidirectional rotation of the washing cylinder during the sudsing operations, and reversal of cylinder rotation after every few revolutions when operating in a bath not containing detergents, for example in the rinsing operation.

An object of the present invention is to provide an improved apparatus for washing textiles in which the mass of fabrics is tumbled in one direction during the washing in a detergent bath and alternately tumbled in opposite directions during the rinsing operations.

A further object is to provide an apparatus for causing a washer cylinder to rotate in one direction only during the sudsing operations and to reverse during the rinsing operations, but which will permit unidirectional rotation during both sudsing operations and rinsing operations when such unidirectional operation is desired.

In the practice of the present invention that point in the complete laundry process which marks the completion of the cleaning operations and which should be followed by the initiation of the rinsing operations may be determined by any preferred means. The application of John W. Chamberlin, Serial No. 747,841, now abandoned, filed May 13, 1947, as a continuation of Serial No. 398,244, filed June 16, 1941, and Patent 2,430,668, Washing Machine and Automatic

Control and Mechanism Therefor, granted November 11, 1947, this patent being a division of Serial No. 398,244, now abandoned, disclose mechanism by means of which the wash liquid is automatically analyzed, and when the analysis indicates that the clothes have been cleaned to the desired extent the mechanism automatically sets in operation certain instrumentalities which perform certain functions, among which are the shutting off of the means for feeding detergent, the dumping of the detergent bath, and the filling of the washer with water up to a predetermined high level, higher than the level of the detergent bath used during the washing operations. This analysis of the wash water according to the Chamberlin applications referred to is accomplished by any one or more of several alternative methods, including the testing of the acidity of the detergent bath, the determination of the cleanliness of the detergent bath by light responsive means, and the testing of the electric conductivity of the detergent bath. Patent 2,422,897 for Art of Cleaning Fabrics, issued to George P. Hebard and Herman E. Sheets, on June 24, 1947, discloses other mechanism for determining the point at which the change from sudsing operations to rinsing operations is to be made, the mechanism referred to being responsive to the suds within the washer. The applications referred to all disclose instrumentalities energized automatically when the point in the laundry process has been reached when the supply of detergent should be shut off, and said Chamberlin applications disclose instrumentalities for shutting off the supply of detergent, discharging the detergent bath, and filling the washer up to the desired level for rinsing.

The present invention is not limited to any particular means for determining the point in the washing program when rinsing operations should be initiated. If preferred, that point may be determined according to the judgment of the operator in each individual washing program. It may be stated briefly that apparatus embodying the principles of the present invention should be responsive to the functions of an instrumentality definitely related to the completion of the sudsing operation and/or the initiation of the rinsing operations.

Referring to the drawings—

Figure 1 is a diagrammatic view of a washer having control means cooperatively associated therewith for governing the admission of detergent, the admission of water, the discharge of liquid, and switch means for determining whether cylinder rotation shall be unidirectional or shall be reversed; and

Fig. 2 is a diagrammatic view of such switch means for determining whether cylinder rotation shall be uni-directional or shall be reversed which is actuated by the water level in the washer and shows the instrumentalities common to the form of the invention shown in Figs. 1 and 2 for carrying out the change-over from uni-directional rotation to rotation periodically reversed in direction.

Referring first to Figure 1, the numeral 1 indicates a washing machine, part of the shell thereof being broken away to show a portion of the rotatable cylinder 2 mounted therein. The shell of the machine 1 is provided with a door 1a. The cylinder 2 is provided with the door 2a, which may be brought into registry with the door 1a for the admission or removal of textile pieces. Said cylinder 2 is carried in trunnions 3

mounted on the shell of the washer 1. Said cylinder 2 is adapted to be driven by the motor 4, which is connected to said cylinder 2 by means of a belt or sprocket chain disposed within the cover 5. Said motor 4 is connected to the three wires of a three-phase electric circuit, to be referred to more in detail presently.

The washer 1 is provided with the valve 9 for the admission of detergent, the valve 10 for the admission of water, and the valve 11 for the discharge of liquid. The Chamberlin applications, above referred to, disclose control mechanisms operating automatically upon the achievement of certain points in the laundry process to energize certain instrumentalities to control admission of detergent, the shutting off of the supply of detergent, the admission of water, the shutting off of the supply of water, the opening of the discharge valve and the closure thereof, as well as other functions not pertinent to this particular invention. Such control mechanisms, or any preferred equivalent or modification thereof, are indicated generally in Figure 1 by the numeral 12, which for the purpose of this description will be referred to as a circuit controller. Said circuit controller 12 is adapted to be operated by means of the ratchet motor 13, which is connected to the electric circuit indicated by the wires 14-14 controlled by the switch 15. Said circuit controller 12 is supplied by an electric circuit indicated by the wires 16-16, the circuit controller 12 having the function of controlling the energization or de-energization of a plurality of control circuits. One of the control circuits, adapted to be energized at one stage of operation of the circuit controller 12, includes the solenoid 17, which controls the detergent valve 9. Another control circuit, adapted to be energized at another stage of operation of the circuit controller 12, includes the solenoid 18 for controlling the water admission valve 10. Another circuit, responsive to the circuit controller 12, includes the solenoid 19 for controlling the discharge valve 11. Another circuit, responsive to the circuit controller 12, includes the solenoid 20 for controlling the switch 21 adapted to bridge or unbridge the relatively stationary contacts 22-22. Said switch 21 is biased to open position, but under the influence of the circuit controller 12 is adapted to be moved to bridging relationship with the contacts 22-22. The switch 15 for controlling the operation of the ratchet motor 13, which in turn operates the circuit controller 12, may be moved in response to the accomplishment of any step, or steps, in the laundry process. For example, said switch 15 may be closed when it has been determined that the clothes in the washer have been cleaned to a predetermined extent, so that the sudsing operations should be discontinued. This point in the washing program bears a definite relationship to the closing of the detergent valve 9, the operation of the discharge valve 11, and the control of the water valve 10 for rinsing purposes.

In short, the control system illustrated in Figure 1 is such that the switch 21 will be moved to closed position when the time has arrived when the sudsing operations should be discontinued, which time has a definite relationship with the time when the detergent valve 9 is moved to closed position, the discharge valve 11 is opened and closed, and the water admission valve 10 is controlled to admit the desired amount of water for rinsing purposes. In other language, the switch 21 is responsive to the operation of control mechanism such for example as that il-

lustrated in the Chamberlin or Hebard and Sheets applications aforesaid, and is adapted to be closed at a point or stage in the program having a definite relationship with the moment at which it is determined that the desired degree of cleaning has been had, which moment bears a definite relationship to the operation of the detergent admission valve 9 and to the operation of the water admission valve 10, as well as the operation of the discharge valve 11.

Referring now to Figure 2, a control mechanism is illustrated for controlling the motor 4 to cause said motor to rotate unidirectionally when the switch 21 is in open circuiting position and to reverse its direction of rotation after every few revolutions when said switch 21 is in closed position.

The switch 21 according to the disclosure in Figure 2 is illustrated as being responsive to the level of liquid within the washer 1, though as shown in Figure 1 said switch 21 may be controlled directly by the circuit controller 12 quite independently of the liquid level within the washer 1. However, for simplicity of disclosure, means have been illustrated for controlling the valve 21 in response to the level of liquid within the washer 1. In usual laundry practice a predetermined lower level, indicated by the numeral 23a, is maintained in the detergent bath during the sudsing operations, whereas during the rinsing operations a predetermined higher level, indicated by the numeral 23b, is maintained. According to usual laundry practice, therefore, the predetermined lower level is an incident to the operations in a detergent bath, and the predetermined higher level is incident to the rinsing operations, in which the percentage of detergent in the bath is reduced, progressively or otherwise, toward a limit of zero.

According to the disclosure of Figure 2, a cylinder 24 is connected to the lower portion of the washer 1. Said cylinder 24 has a float 24a mounted therein, which is connected to the switch 21. When the liquid in the washer 1 is at the predetermined high level 23b incident to the rinsing operation, the switch 21 is in bridging relationship with the contacts 22-22.

When said switch 21 is in this circuit closing position, whether due to the automatic control 50 12 is shown in Fig. 1 or the float 24a shown in Fig. 2, the motor 4 will be controlled to impart rotation to the cylinder 2 throughout a few revolutions in one direction alternately with a few revolutions in the opposite direction. When said 55 switch 21 is in open circuiting position said motor 4 will impart unidirectional rotation to said cylinder 2. The instrumentalities for accomplishing the differences in cylinder rotation just referred to will now be described.

The numerals 25, 26 and 27 indicate the three wires of a three-phase electric supply system. A solenoid 28 controls a three-blade switch 28a to connect the three wires of the three-phase supply system to the three wires 29, 30 and 31. The numerals 34, 35 and 36 indicate three wires connected to the motor 4. The connections of said three wires 34, 35 and 36 to the wires 29, 30 and 31 are controlled by the three-blade switch 37 (responsive to the solenoid 38) and the three-blade switch 39 (responsive to the solenoid 40). As will be explained presently, when said switch 37 is in closed position said switch 39 will be in open position, and, conversely, when said switch 37 is in open position said switch 39 will be in closed position. In other words, solenoids 38 and

40 will be alternatively energized and alternatively de-energized.

In the system illustrated, wire 36 is connected to wire 31 through either switch 37 or 39. However, wire 34 is connected to wire 29 when switch 37 is closed and is connected to wire 30 when switch 39 is closed; wire 35 is connected to wire 30 when switch 37 is closed and is connected to wire 29 when switch 39 is closed. In other words, the alternate operations of switches 37 and 39 result in reversing the connections of the motor 4 to two of the three wires (29 and 30) of the three-wire, three-phase electric supply system 25, 26, 27, thereby causing reversals in the direction of rotation of the rotor of said motor.

The numeral 41 indicates a switch adapted to cooperate with the contact 42 and biased to open circuit position by means of the spring 43. The numeral 44 indicates a switch adapted in its upper position to engage the contact 45 and in its lower position to engage the contact 46. Said switch 44 is biased upwardly by means of the spring 47. In other words, said switch 44 is biased to engagement with the contact 45 and out of engagement with the contact 46. Said switch 41 is swung about the axis 48 and the switch 44 is swung about the axis 49. Said switches 41 and 44 are adapted to be moved in unison by the rod 50 provided with the abutment members 51 and 52. Said rod 50 has sliding engagement with the switches 41 and 44 whereby upward movement of the rod 50 will swing the switches 41 and 44 in a clockwise direction. Said switches 41 and 44 are adapted to be latched in their unbiased positions by means of the latch members 53 and 54 respectively, said latch members 53 and 54 being biased to latching position by the springs 55 and 56 respectively. Said rod 50 may be manipulated by means of the handle 57 swung about the axis 58. Said latching member 53 is provided with the hand grip portion 59 whereby said latching member 53 may be moved manually to unlatching position. Cooperating with the latching member 53 is the solenoid 60, which when energized will move the latching member 53 to unlatching position whereby the spring 43 may move the switch 41 to open circuit position. The latching member 54 is controlled by the solenoid 61. The solenoid 61 is connected in a circuit controlled by the switch 21. As clearly shown in Figure 2, the energization of the solenoid 28 is responsive to the switch 41, said solenoid 28 being connected in a circuit leading from the wire 26 through the conductor 62 to the switch 41, thence through the contact 42 and conductor 63 and solenoid 28 to the wire 25. When the switch 41 has been brought into engagement with the contact 42 the solenoid 28 will close the switch 28a and hold said switch closed, whereby to energize the wires 29, 30 and 31.

The switch 44 when in its lowermost position, that is—in its latched position in engagement with the contact 46, completes a circuit which leads from the wire 30 through the solenoid 38, conductor 64, contact 46, switch 44, conductor 65 and conductor 66 to the wire 29. The resulting energization of the solenoid 38 closes the switch 37, which, as noted above, results in energization of the motor 4 for unidirectional rotation, which may be considered for the purpose of this description as being forward rotation. The upper contact 45 cooperating with the switch 44 is connected through the conductor 67 to the switch 68, which is adapted to be moved into contact either with the contact 69 or contact 70. Con-

tact 69 is connected to the electric timer motor 71, which through the conductor 72 is connected to the wire 30. When said switch 68 is in engagement with the contact 70, connection is made with the wire 30 through the solenoid 38.

The electric motor 71 is adapted to drive the shaft 73 provided with the two segment members 74 and 75. Said segments 74 and 75 are adapted to provide alternative electrical connections between the shaft 73 and the conductors 76 and 77 respectively. Conductor 76 leads to the solenoid 49 and thence through the conductor 78 to the wire 30. Conductor 77 leads to the solenoid 38 and thence to the wire 30. The shaft 73 is connected electrically with the contact 69 through the conductor 6 so that current can flow through the circuits controlled by cams 74, 75 only while the electric motor 71 is running. The solenoid 61 is located in the following circuit across the wires 29 and 30: from wire 29 through conductor 66, switch 21, conductor 79, solenoid 61, conductor 80 to the wire 30.

The mode of operation of the above described instrumentalities is substantially as follows:

The clothes to be washed will be loaded into the cylinder 2, the door 2a thereof being brought into alignment with the door 1a of the washer shell. Water will be added together with soap or other detergents. This detergent bath will have a level, as indicated by the numeral 23a in Figure 2, lower than the level used in rinsing operations, which latter level is indicated by the numeral 23b. The operator will swing the handle 57 in a clockwise direction, lifting the rod 50. Collars 51 and 52 will swing the switches 41 and 44 respectively in a clockwise direction into engagement with their respective contact members 42 and 46. Latching members 53 and 54 will hold said switches 41 and 44 in the positions just referred to. The operator may release the handle 57, which resumes the position illustrated in Figure 2.

Switch 41 has established a circuit from the wire 26, conductor 62, through contact 42, conductor 63 and solenoid 28 to the wire 25. Solenoid 28 will be energized to close the switch 28a and to retain it in closed position.

The lower switch 44 completes a circuit from the wire 30 through the solenoid 38, conductor 64, contact 46, switch 44, conductor 65, conductor 66 to wire 29. Energization of the solenoid 38 will close the switch 37. Inasmuch as switches 28a and 37 are now closed, and inasmuch as the closure of switch 37 connects the motor 4 to run in the forward direction, rotation in a forward direction will be communicated to the cylinder 2 within the washer 1. After the fabrics have been so treated in a sudsing operation for the desired length of time, the discharge valve 11 may be opened to discharge the spent detergent bath, after which said discharge valve 11 may be closed and fresh water and fresh detergent may be added through operation of the valves 10 and 9 respectively. Successive sudsings may be had according to any preferred program.

The present invention provides means whereby when it has been determined that the sudsing operations should be discontinued and the rinsing operations commenced, the unidirectional forward rotation of the cylinder washer 2 will be discontinued and said cylinder washer will be caused to operate with periodic reversals.

Expressed in other language, according to the present invention the sudsing operation is carried on in a washer wherein the washer cylinder

2 rotates in one direction only. During the rinsing operations the direction of rotation of the washer cylinder should be periodically reversed in the case of certain types of washer load, though in the case of other types of washer load unidirectional rotation should be continued.

As indicated above, the moment when the change-over from unidirectional rotation to reversal of rotation is to be accomplished may be determined in any preferred way. For example, it may be determined by the functioning of instrumentalities operating automatically, as illustrated in the Chamberlin applications and in the Hebard and Sheets applications aforesaid. Means for determining the moment when the change-over from unidirectional cylinder operation to reversal of cylinder operation is to occur are indicated schematically by the controller 12 (Fig. 1). The time for such change-over may be a moment having a definite relationship with the closure of the detergent inlet valve 8 in connection with the last sudsing operation before a rinsing operation is to be initiated, or the moment of change-over may be determined by means responsive to the higher liquid level incident to rinsing operations. If preferred, the time of such change-over may be determined automatically according to the reading of an instrumentality responsive to the amount of detergent in the liquid bath in the washer, or according to the lubricating qualities of said bath.

For simplicity of illustration the mechanism for accomplishing the change-over from unidirectional rotation of the washer cylinder 2 to reversal of rotation thereof has been illustrated in Figure 2 as being responsive to the level of the liquid bath within the washer 1, the lower level being incident to the sudsing operations, the higher level being incident to the rinsing operations. At this higher level the float in the cylinder 24 holds the switch 21 in bridging relationship with the contacts 22-22. At lower levels of the bath the switch 21 is out of bridging relationship with said contacts. When the switch 21 bridges the contacts 22-22 instrumentalities are brought into service for causing the cylinder reversal referred to, as follows: Circuit is completed from the wire 29, conductor 66, switch 21, conductor 79, solenoid 61, conductor 86 to the wire 30. The resulting energization of the solenoid 61 causes the release of the switch 44, resulting in the disengagement of switch 44 from the contact 46, thereby de-energizing the solenoid 38, resulting in the opening of the switch 37. Release of the switch 44 causes engagement thereof with the contact 45, thereby establishing a circuit from the wire 29, through conductor 66, conductor 65, switch 44, contact 45, switch 68, contact 69, timer motor 71 and line 72, to the wire 30. The timer motor is thereby set into operation for rotating the shaft 73. The cams 74 and 75 mounted upon said shaft 73 completes circuits alternately from the wire 36, conductor 68 and shaft 73, as follows: (a) through cam 75, conductor 71, solenoid 38 to the wire 30, and (b) through cam 74, conductor 76, solenoid 40 and conductor 78 to the wire 30. Solenoids 38 and 40 will thereby be alternately energized, resulting in the alternate closure of their corresponding switches 37 and 39, thereby alternately connecting the motor 4 for rotation in opposite directions. Accordingly, during the rinsing operations, the initiation of which is accompanied by the engagement of the switch 21 with the contacts 22-22, the washer cylinder 2 will be periodically reversed, the periods

between reversals being determined by the operation of the timer motor 71.

The laundry machine will continue in its reversal operation until stopped by opening of the switch 41, which may be accomplished manually by means of the hand grip 59 or automatically by energization of the solenoid 60. Said solenoid may be energized in response to any preferred mechanism, as for example in response to the operation of the circuit controller 12 (Fig. 1). Opening of the switch 41 will result in the de-energization of the solenoid 28 and the opening of the main switch 28a.

In many instances it will be preferred to operate the washer cylinder 2 with unidirectional rotation not only during the sudsing operations but during the rinsing operations as well. This is particularly true when the fabric being washed is carried in nets, or where the pieces being washed are of such a nature that they do not have a decided tendency to tangle. The present invention therefore makes provision for the choice of unidirectional operation throughout the washing operation if preferred. For accomplishing this result utilization is made of the switch 68 which is normally in contact with 69. When the switch 68 is moved upwardly to engage the contact 70, the timer motor 71 and the solenoid 40 are thrown out of circuit, it being remembered that the shaft 73 of the timer motor 71 is biased to open circuit relationship with the conductor 76. The solenoid 38 is in circuit whether the switch 44 is in its uppermost or its lowermost position. Accordingly, if unidirectional cylinder rotation is desired throughout the washing period the operator will move switch 68 into engagement with the contact 70, whereby circuit is complete from the wire 29, conductor 66, conductor 65, switch 44, contact 45 or contact 46, depending upon the position of the switch 21, through solenoid 38 to wire 30. In either case the solenoid 38 is energized to hold the switch 37 in closed position for unidirectional forward rotation. Accordingly there will be no reversal in the direction of rotation of the cylinder 2 either during the sudsing operations or the rinsing operations.

Though certain preferred embodiments of the present invention have been described in detail, many modifications will occur to those skilled in the art. It is intended to cover all such modifications that fall within the scope of the appended claims.

What is claimed is:

1. Apparatus for washing and rinsing textile pieces, comprising, a washing cylinder mounted on a horizontal axis adapted to contain the pieces, a shell adapted to contain a bath into which the cylinder dips, an electric motor drive for the cylinder, supply wires leading to the motor, a solenoid-operated switch between the supply line and the motor adapted to connect the motor for forward rotation, a second solenoid-operated switch also adapted to connect the supply line to produce reverse rotation, a control circuit adapted to be closed by the operator, a solenoid in the control circuit adapted to close said switch giving forward rotation, a float controlled by the level of the liquid in the container adapted to open said control circuit, a second control circuit closed by the opening of the first circuit, automatic means in the second control circuit to alternately energize the solenoids giving forward and reverse rotation.
2. Apparatus for washing and rinsing textile

11

pieces, comprising a washing cylinder mounted on a horizontal axis adapted to contain the pieces, a shell adapted to contain a bath into which the cylinder dips, an electric motor drive for the cylinder, current supply wires, a solenoid-operated switch between the supply wires and the motor adapted to connect the motor for forward rotation, a second solenoid-operated switch also adapted to connect the supply wires to produce reverse rotation, a control circuit adapted to be closed by the operator to close said first named solenoid switch giving forward rotation while the bath remains at a level used for washing, a float controlled by the level of the liquid in the container adapted to open said control circuit when the bath depth is at a level for rinsing, a second control circuit closed by the opening of the first circuit, automatic means in the second control circuit to alternately energize the first and the second solenoid-operated switches alternating giving forward and reverse rotation while rinsing is in progress.

3. In a washing apparatus, in combination, a washer shell, a clothes-containing cylinder mounted for rotation within the shell about a horizontal axis, electrical means adapted to rotate said cylinder in either direction, a timing motor for periodically reversing the direction of rotation, a circuit by-passing said timer to cause the cylinder to be normally rotated in one direction, means for filling the shell to a low level suitable for washing and to a higher level suitable for rinsing, a switch responsive to the rise of the level of the bath from the low to the high level which opens said by-pass circuit and causes the timer motor to function to thereafter periodically

5

12

reverse the direction of rotation of said cylinder. 4. In a washing apparatus, in combination, a washer shell, a clothes-containing cylinder mounted for rotation within the shell about a horizontal axis, electrical means adapted to rotate said cylinder in either direction, a timing motor for periodically reversing the direction of rotation, a circuit by-passing said timer to cause the cylinder to be normally rotated in one direction, means for filling the shell to a low level suitable for washing and to a higher level suitable for rinsing, a switch responsive to the rise of the level of the bath from the low to the high level which opens said by-pass circuit and causes the timer motor to function to thereafter periodically reverse the direction of rotation of said cylinder, and manually operated means for maintaining uni-directional rotation regardless of the depth of water by disabling the reversing mechanism.

GEORGE G. GAUBATZ.
